UNITED STATES PATENT OFFICE

BO FOLKE RANDEL, OF SAN DIEGO, CALIFORNIA, ASSIGNOR TO C. A. DUNHAM COMPANY,
OF MARSHALLTOWN, IOWA, A CORPORATION OF IOWA

REFRIGERATING APPARATUS AND METHOD

Application filed September 24, 1928. Serial No. 307,979.

My invention relates to refrigerating apparatus and the objects thereof are: First, to provide a refrigerating apparatus which is adapted to operate under a relatively low pressure; second, to provide a process in which refrigeration is brought about by the action of an inert gas on a rich solution of gas in liquid whereby the latter is weakened causing an absorption of heat and consequent refrigeration within portions of the apparatus; third, to provide a process of this class in which circulation within the apparatus is maintained by the creation of a differential of pressure by means of a fluid pump; fourth, to provide a process of this class in which a primary and tertiary medium having great affinity for each other are associated with a secondary inert medium adapted to cause disassociation of said primary and tertiary medium under conditions of great temperature reduction; fifth, to provide an apparatus of this class in which a rich solution of a primary and tertiary medium may be readily weakened by a certain action of a secondary, relatively inert medium causing a reduction in temperature to said solution; sixth, to provide a process of refrigeration in which the various mediums employed are not in any way altered in form during the process, such as changing from gas to liquid form and vice versa but retain their initial form throughout the entire process, except such altering as is due to the solution of a vapor in a liquid, and seventh, to provide a process and apparatus of this class which are simple, conservative in space requirement, self contained and economical of operation.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a diagrammatical view of the apparatus employed in my refrigerating system showing certain parts and portions in

section and other parts broken away in order to more clearly illustrate the invention, and Fig. 2 is a sectional view through 2-2 of Fig. 1.

Similar characters of reference refer to similar parts and portions throughout the several views of the drawings.

The evaporator 1, refrigerating element 2, absorber 3, diffusion element 4, cooling jacket 5, vapor control valves 6, and 6a, liquid control valves 7, and 7a, vacuum chamber 8, circulating pump 9, motor 10, pressure chamber 11, transfer pump 12, and refrigerator 13, constitute the principal parts and portions of my refrigerating apparatus.

The evaporator 1, communicates through the refrigerating element 2 and pipe 2a with a vacuum chamber 8. The flow of liquid from the refrigerating element 2 to the vacuum chamber 8, is controlled by the liquid control valve 7. The pressure chamber 11 connects with the evaporator 1, through pipe 11a, terminating in a perforated element 11b shown best in Fig. 2, allowing a gas to issue and bubble through the liquid in evaporator 1. Through the pipe 1a, gas or vapor from the evaporator 1 is led to the diffusion element 4. This diffusion element which may be made in the form of a straight tube as shown, or may be made in a spiral shape or any other suitable shape to provide necessary length to accomplish its purpose, is made of a porous material so constituted as to permit rapid diffusion of a light gas through its walls, but retarding and partially preventing the diffusion of a heavy gas therethrough. A mixture of gases of different densities passing through this diffusion element may therefore be partially separated into its different parts, the lighter gas diffusing through its walls to the outside, while the heavier gas will pass through the inside of the element to the discharge end.

The diffusion element 4 is in communication through pipe 4a with the vacuum chamber 8, the flow of gas to said chamber being controlled by vapor control valve 6. The evaporator 1 is also in communication through the pipe 3a with absorber 3 permitting liquid to flow from said absorber to said

evaporator. The pressure in the evaporator and absorber being equal the liquid in both will be retained at the level shown by line 14. It may be desired for structural reasons to install the evaporator 1 at a higher elevation than the absorber 3, therefore a pump 12 has been introduced in the pipe 3a to force the liquid to a higher level than 14, however, it is obvious that this pump 12 may be omitted except for this purpose. The pressure chamber 11 communicates by pipe 11c with the absorber. Said absorber is fitted with a perforated plate or screen 3a, permitting any liquid coming from the pressure chamber to break up in a fine spray during the descent through the absorber, thus more readily absorbing any absorbable vapors in said absorber. The pressure chamber 11 also communicates at 11d with circulating pump 9, driven by motor 10 or any other suitable motive power. The discharge from this circulating pump 9 leads into the vacuum chamber 8, into eductor nozzles 8a and finally discharging in pressure chamber 11 at 11e. As the pressure chamber is partly filled with liquid, the action of the circulating pump 9 forcing liquid through eductor nozzles 8a, will cause a lowering of the pressure in the vacuum chamber 8, and by the exhausting of liquid and vapors from this vacuum chamber, adding same to content in pressure chamber 11, will at the same time cause an increase of the pressure in the pressure chamber.

It is this difference of pressure in the vacuum and pressure chambers caused by the action in the eductor nozzles, which creates a general circulation of the mediums through the apparatus. The pressure difference will be equal to the height of liquid column H in the evaporator 1. Any further increase of pressure in the pressure chamber will cause vapors to flow through 11a to 11b, bubbling up through the liquid in the evaporator 1. This flow is also controlled by control valve 7a. It being noted that the pressure difference will cause a general circulation of liquid from the evaporator 1 down through the refrigerating element 2 into the vacuum chamber 8, raising the level 15 of the liquid in the pressure chamber 11, causing a further flow of liquid from the pressure chamber 11, through the pipe 11c to the absorber 3, the height H from the level 15 to the inlet of the absorber being the same as the height H in the evaporator 1. This flow is controlled by the valve 6a. By controlling the flow by valves 6a and 7a, the height H may be varied in the absorber and evaporator, and need not be the same in these two elements. From the absorber the liquid will flow by gravity or by means of the pressure pump 12, back to the evaporator 1. There will also be created a general circulation of gases or vapors from the evaporator 1 through the pipe 1a, to the diffusion element 4, thence through

same and through the pipe 4a to the vacuum chamber 8, thence to the pressure chamber 11 and through the pipe 11a back to the evaporator 1, bubbling through any liquid contained in said evaporator.

The absorber 3 is surrounded by the cooling jacket 5, containing cooling water, entering at 5a and discharging at 5b. The absorber may also be constructed so as to permit air cooling.

My process of refrigeration is based upon the following,

First: The fact that a gas in solution in a liquid may be removed from this liquid by bubbling a foreign gas through the solution, provided that this foreign gas is chemically inert to the first mentioned gas and to the liquid.

Second: That a mixture of gases of different densities may be separated by permitting the lighter gas to diffuse through porous membranes.

Third: That certain gases in being absorbed in liquids will generate heat, and conversely, when again separated from the liquid heat will be absorbed.

In carrying out the process of refrigeration within my apparatus, I employ three or more mediums which I preferably refer to as primary or refrigerating medium, and second and tertiary supplementary mediums. The primary medium is a fluid which under normal conditions remains in vapor form and which as will be shown later, remains in this form during the process of refrigeration in my apparatus except as to such change in form as accompanies an absorption in a liquid. The tertiary is a fluid which under normal conditions remains a liquid and as will also be hereinafter shown, remains in this form during the process of refrigeration in my apparatus. The tertiary medium has a strong affinity for the primary medium absorbing same and generating heat during this action. The secondary medium employed however, is practically inert in respect to both the primary and tertiary mediums. The secondary medium is in the form of a gas and remains in this form during the entire process of refrigeration.

As suitable primary mediums may be mentioned, ammonia, sulphur dioxide, hydrogen chloride. As secondary mediums: hydrogen, nitrogen, air, carbon dioxide, butane gas or other hydro-carbon gas, etc., and as tertiary medium: water, alcohol, ether, water with calcium-chloride, water with potassium-carbonate, etc. While certain mediums have thus been mentioned, I do not wish to be limited to the use of such mediums as it is obvious that many others are also well suited for the purpose as my apparatus will operate with any combination of mediums having in general the same characteristics as the ones mentioned.

For the purpose of explaining the action taking place during the process of refrigeration within the apparatus, it will be assumed that the primary medium employed is ammonia vapor; second medium is nitrogen, and the tertiary medium is water with calcium-chloride in solution, the calcium-chloride being introduced to prevent freezing of water. The system is charged with the three 5 mediums (not considering the fourth, calcium-chloride), so that water in the bottom of the absorber 3 and in the evaporator is highly charged with ammonia gas, so called strong liquor, and water in the pressure chamber 11 is slightly charged with ammonia gas, or so 10 called weak liquor. Also the vapor above the liquid levels is mainly nitrogen gas. Now when the circulating pump is started, pressure will increase in the pressure chamber 11 and a general circulation of liquid and vapors 15 will occur as described above. Nitrogen while bubbling through the strong liquor in the evaporator will cause the ammonia gas to evaporate and mix with the nitrogen gas. The temperature of the rich liquor will be 20 lowered, and heat will be absorbed from the surrounding refrigerator.

As the liquor flows downwardly in the opposite direction to the bubbles it becomes 25 weaker and weaker and will absorb more and more heat. The flow is controlled by the control valve 7 so as to allow sufficient time for nearly all the ammonia to be driven out, so that the liquor passing through the refrigerating element is mainly water. The mixed 30 gases will pass to the diffusion element 4. There, the light ammonia gas will pass quickly through the walls, while the nitrogen will pass to the vacuum chamber 8. The length 35 of the travel through this diffusion element is adjusted so as to free the mixture of practically all the ammonia gas, before the end of the element is reached.

The weak liquor in the pressure chamber 40 11 will be forced up through the pipe 11c and into absorber 3. In descending through this absorber, the now cool and weak liquor being in good condition to reabsorb ammonia gas will absorb this gas which has diffused 45 through the walls of the diffusion element, and will cause a still more rapid flow of ammonia gas through the walls by creating a pressure difference as far as this ammonia gas concerns between the outside and inside 50 of this diffusion element. Nitrogen gas, being practically insoluble in water, no such pressure difference will occur as far as this nitrogen gas is concerned, and once an equal 55 pressure on this nitrogen gas has been established inside and outside the diffusion element, no further diffusion of the nitrogen gas will occur.

Any ammonia gas not diffused through to 60 the absorber will be absorbed in being mixed

with weak liquor in the vacuum chamber 8 and the pressure chamber 11.

When ammonia gas is reabsorbed in the absorber 3, heat will be generated, which heat is removed by cooling water or by atmosphere as desired, and the same amount of heat which is thus generated and removed from the absorber, will later be absorbed in the evaporator, causing refrigeration.

It should be noted that while the motive power in a mechanical sense is much smaller in my process than in any other, being only the small power necessary to cause circulation against very small pressure difference, the motive power from a thermodynamic 75 sense is practically the same. The refrigerating effect of any system is dependent upon the removal of heat in a condenser from a medium, which is changed from vapor form to liquid form. By my process a somewhat 80 similar transfer of heat occurs in an absorber, and a gas is going through an action of being considerably reduced in volume by being absorbed in a liquid. The difference between 85 my process and older processes is the fact that 90 high pressure is not required to cause this reduction of volume. It should also be noted that my apparatus is constructed according to counter flow principles, the mediums which are separated or combined in the absorber and evaporator flowing in opposite 95 directions, thus increasing the effectiveness of the apparatus.

Though I have described a particular apparatus and agents for obtaining refrigeration, I do not wish to be limited to this particular apparatus and these agents, but desire to include within the scope of my invention the apparatus and agents as set forth 100 in the appended claims.

Having thus described my invention, what I claim as new and desire to secure by Letters Patent is:

1. In a refrigerating apparatus, a circulating system containing a solution of a soluble gas in a liquid, and a relatively inert gas, said system including means for causing circulation of the liquid and gas, means for causing said inert gas to effect a separation of said soluble gas from the solution under absorption 110 of heat and consequent refrigerating action, means for causing mixing of said inert gas with said soluble gas after said separation has taken place and further means for causing a partial separation of the said soluble 115 gas from the said inert gas by permitting the lighter gas to diffuse through a diffusion member at a greater velocity than the heavier gas, and means for again absorbing the soluble gas in the liquid.

2. A process of refrigeration consisting in bubbling a relatively inert gas through a solution of a liquid and a soluble gas so as to cause the release of a portion of the soluble gas, utilizing the weakened solution to absorb heat in 120 125

a refrigerating coil, separating the released soluble gas from the inert gas by diffusing the soluble gas through a diffusion member, re-absorbing the soluble gas in the weakened so-
5 lution, and dissipating the heat thus released.

3. In an absorption refrigerating process, the step of passing a mixture of soluble and inert gases through a porous receptacle from which the soluble gas will diffuse at a greater
10 rate than the inert gas, and passing a liquid about the porous receptacle whereby the soluble gas will be absorbed in the liquid.

4. In an absorption refrigerating process, the step of passing a mixture of soluble and inert gases in one direction through a porous receptacle from which the soluble gas will diffuse at a greater rate than the inert gas, and passing a liquid in the opposite direction about the receptacle whereby the soluble gas
20 will be absorbed in the liquid.

5. An absorption refrigerating process in which a liquid is mechanically forced to circulate from a pressure chamber through an exhausting chamber and thence back to the
25 pressure chamber thus causing three other fluid circulations as follows: a circulation of a portion of the liquid from the pressure chamber through an absorption space, an evaporation space, a refrigerating space, the
30 exhausting chamber and back to the pressure chamber, a circulation of inert gas from the pressure chamber through the evaporation space, the absorption space, the exhausting chamber and back to the pressure chamber,
35 and a circulation of soluble gas from the evaporation space with the inert gas to the absorption space, thence in solution in the liquid back to the evaporation space.

6. In an absorption refrigerating apparatus, an absorber comprising an outer receptacle, means for conducting a liquid into the upper portion of the receptacle and removing the liquid from the lower portion of the receptacle, a porous receptacle enclosed within
45 the outer receptacle, means for conducting a mixture of inert and soluble gases into the lower portion of the porous receptacle, and means for withdrawing the inert gas from the upper portion of the porous receptacle.

50 7. In an absorption refrigerating apparatus, an absorber comprising an outer receptacle, an intermediate receptacle enclosed within the outer receptacle, a porous receptacle enclosed within the intermediate receptacle, means for circulating a heat-removing fluid through the outer receptacle, means for conducting a liquid into the upper portion of the intermediate receptacle and removing the liquid from the lower portion of the intermediate receptacle, means for conducting a mixture of inert and soluble gases into the lower portion of the porous receptacle, and means for withdrawing the inert gas from the upper portion of the porous receptacle.

55 8. A refrigerating apparatus comprising

a jet exhauster and a pressure chamber, means for circulating a liquid from the pressure chamber through the jet exhauster and back to the pressure chamber, an evaporator, a refrigerating coil, an absorber, means comprising
70 the exhauster for circulating a liquid from the pressure chamber through the absorber, the evaporator and the refrigerating coil back to the pressure chamber, and means also including the exhauster for circulating
75 an inert gas from the pressure chamber through the evaporator, and the absorber back to the pressure chamber, said latter means also including a conduit through which a soluble gas is conveyed along with the inert
80 gas from the evaporator to the absorber.

9. A refrigerating apparatus comprising a jet exhauster and a pressure chamber, means for circulating a liquid from the pressure chamber through the jet exhauster and
85 back to the pressure chamber, an evaporator, a refrigerating coil, an absorber comprising an inner porous chamber and an outer non-porous chamber, in which the inner
90 chamber is enclosed, means comprising the exhauster for circulating a liquid from the pressure chamber through the outer chamber of the absorber, the evaporator and the refrigerating coil back to the pressure chamber, and means also including
95 the exhauster for circulating an inert gas from the pressure chamber through the evaporator and the inner porous chamber of the absorber back to the pressure chamber, said latter means also including a conduit
100 through which a soluble gas is conveyed along with the inert gas from the evaporator into the porous chamber.

10. A refrigerating apparatus comprising a jet exhauster and a pressure chamber, means for circulating a liquid from the pressure chamber through the jet exhauster and back to the pressure chamber, an evaporator, a refrigerating coil, an absorber comprising an inner porous chamber and an outer non-porous chamber in which the inner chamber is enclosed, means for dissipating heat from the outer chamber, means comprising the exhauster for circulating a liquid from the pressure chamber through the outer chamber of the absorber, the evaporator and the refrigerating coil back to the pressure chamber, and means also including the exhauster for circulating an inert gas from the pressure chamber through the evaporator and the inner porous chamber of the absorber back to the pressure chamber, said latter means also including a conduit through which a soluble gas is conveyed along with the inert
110 gas from the evaporator into the porous chamber.

11. A refrigerating apparatus comprising a suction chamber and a pressure chamber, means for circulating fluids between these chambers to maintain a pressure difference
115

therebetween, an evaporator, a refrigerating coil, an absorber, conduits for circulating a liquid from the pressure chamber through the absorber, the evaporator, and the refrigerating coil to the suction chamber, and conduits for circulating an inert gas from the pressure chamber through the evaporator and the absorber to the suction chamber, said latter conduits including a conduit through which a soluble gas is conveyed along with the inert gas from the evaporator to the absorber.

12. A refrigerating apparatus comprising a suction chamber and a pressure chamber, means for circulating fluids between these chambers to maintain a pressure difference therebetween, an evaporator, a refrigerating coil, an absorber comprising an inner porous chamber and an outer non-porous chamber in which the inner chamber is enclosed, conduits through which a liquid is circulated from the pressure chamber through the outer chamber of the absorber, the evaporator and the refrigerating coil to the suction chamber, conduits through which an inert gas is circulated from the pressure chamber through the evaporator and the porous chamber of the absorber to the suction chamber, said latter conduits including a conduit through which a soluble gas is conveyed along with the inert gas from the evaporator into the porous chamber.

13. A refrigerating apparatus comprising a suction chamber and a pressure chamber, means for circulating fluids between these chambers to maintain a pressure difference therebetween, an evaporator, a refrigerating coil, an absorber comprising an inner porous chamber and an outer non-porous chamber in which the inner chamber is enclosed, means for dissipating heat from the outer chamber, conduits through which a liquid is circulated from the pressure chamber through the outer chamber of the absorber, the evaporator and the refrigerating coil to the suction chamber, conduits through which an inert gas is circulated from the pressure chamber through the evaporator and the porous chamber of the absorber to the suction chamber, said latter conduits including a conduit through which a soluble gas is conveyed along with the inert gas from the evaporator into the porous chamber.

In testimony whereof, I have hereunto set my hand at San Diego, California, this 17th day of September, 1928.

BO FOLKE RANDEL.
